UNITED STATES PATENT OFFICE.

ADELBERT O. BENECKE, OF BOSTON, MASSACHUSETTS, ASSIGNOR TO CROSBY STEAM
GAGE & VALVE COMPANY, OF BOSTON, MASSACHUSETTS, A CORPORATION.

ENGINE-INDICATOR.

1,336,810.

Specification of Letters Patent. Patented Apr. 13, 1920.

Application filed January 8, 1915, Serial No. 1,201. Renewed September 28, 1919. Serial No. 325,816.

To all whom it may concern:

Be it known that I, ADELBERT O. BENECKE, a citizen of the United States, and a resident of Boston, in the county of Suffolk and 5 State of Massachusetts, have invented certain new and useful Improvements in Engine-Indicators, of which the following is a specification.

This invention relates to that form of engine indicators in which the pencil mechanism is operated by a piston and the pencil travels vertically along the surface of a reciprocating drum and the object of the invention is to cushion the pencil directly and 15 independently rather than by means of the resilient pencil arm heretofore employed.

The invention is illustrated by the accompanying drawings in which:—

Figure 1 is a vertical central sectional 20 view of an indicator;

Fig. 2 is a plan view of said mechanism looking from above; and

Fig. 3 is a section on the line 3—3 Fig. 1.

The steam cylinder 1 is furnished with 25 the piston 2 and piston rod 3 engaging at its upper end the pencil arm 4 pivoted at 5 to the support 6 rotatably mounted in the top of the steam cylinder casing 7. The pencil arm 4 is slotted at 8 to slidably engage the top of the piston rod 3 and is also slotted at its outer end 9 to slidably engage the pencil holder 10. The support 6 is furnished on its outer end with a projection 11 in which are mounted vertical parallel bars 30 12 furnishing a vertical guideway for the pencil holder 10 and also lateral support for the outer end of the pencil arm. This pencil holder comprises a tubular socket 13 in which said pencil is slidably mounted being 35 flanged at its inner end to engage a corresponding shoulder in said cylinder and abutting against a spring 14 disposed therein. The support 6 is furnished with the handle 15 by which it may be manipulated and the 40 cylinder casing 7 is furnished with the adjustable stop 16 to limit the movement of said support toward the drum 17. In operation the parts are so adjusted that, when in 45 the position shown in the drawings, the pencil, cushioned by spring 14, impinges upon the chart, being held in that position by means of the handle 15, the pencil arm 4 being employed simply to raise and lower the pencil and not, as heretofore, also as a cushion, or yielding support therefor.

I claim:

1. In an engine indicator of the character described, in combination, a cylinder; a piston therefor; a piston rod; a pencil mechanism support rotatably mounted on the cylinder and furnished with a vertical guideway; a pencil arm pivoted to the support and in slotted engagement with the piston rod; and a pencil in slotted engagement with the pencil arm and laterally confined by the guideway and vertically movable therein.

2. In an engine indicator of the character described, in combination, a cylinder; a piston therefor; a piston rod; a pencil mechanism support rotatably mounted on the cylinder and furnished with a vertical guideway; a pencil arm pivoted to the support and in slotted engagement with the piston rod; a pencil in slotted engagement with the pencil arm and laterally confined by the guideway and vertically movable therein; and a controlling spring for the pencil.

3. In an engine indicator of the character described, in combination, a cylinder; a piston therefor; a piston rod; a pencil mechanism support rotatably mounted on the cylinder and furnished with a vertical guideway; a pencil arm pivoted to the support and in slotted engagement with the piston rod; a pencil in slotted engagement with the pencil arm and laterally confined by the guideway and vertically movable therein; and adjustable means for limiting the rotatability of the pencil mechanism support.

4. In an engine indicator of the character described, in combination, a cylinder; a piston therefor; a piston rod; a pencil mechanism support rotatably mounted on the cylinder and furnished with a vertical guideway; a pencil arm pivoted to the support and in slotted engagement with the piston rod; a pencil in slotted engagement with the pencil arm and laterally confined by the guideway and vertically movable therein; a controlling spring for the pencil; and adjustable means for limiting the rotatability of the pencil mechanism support.

In testimony whereof I have affixed my signature in presence of two witnesses.

ADELBERT O. BENECKE.
